FRED OSBORNE, OF BIRMINGHAM, ALABAMA, ASSIGNOR TO THE BARRETT COMPANY, OF NEW YORK, N. Y., A CORPORATION OF NEW JERSEY

DISTILLATION OF TAR, ETC.

Application filed February 26, 1927. Serial No. 171,154.

This invention relates to improvements in the distillation of tar and the production of pitches, and includes a new method of tar distillation and pitch production and improvements in apparatus therefor. More particularly, the invention relates to improvements in the distillation of coal tar and the production of pitches at coal distillation plants, such as by-product coke oven, 10 gas oven or gas retort plants.

In the ordinary operation of by-product coke ovens the gases produced by the coking operation pass from the individual ovens through individual uptake pipes and goose-necks to a collector main or mains common 15 to a battery of ovens. The coke oven gases leaving the ovens at a high temperature are cooled to separate tar constituents therefrom, the tar constituents being separated partly 20 in the collector mains and partly in subsequent condensers.

Coal tar produced at by-product coke ovens is commonly shipped or conveyed to tar distillation plants where it is subjected to 25 distillation for the recovery of coal tar distillates and the production of pitches as residues of the distillation.

The present invention provides an improved process of and apparatus for distillation of tar for the production of pitch at 30 a coke oven plant, and with recovery of the volatile oils from the distillation along with the lighter tars and oils from the coke oven plant. More particularly, the invention relates 35 to improvements in the distillation of tar with hot coke oven gases in modified uptake pipes located between the coke oven and the collector main.

When tar is distilled by atomizing or 40 spraying it into the hot coke oven gases as they pass through the uptake pipes on their way from the coke ovens to the collector main, the volatile oils driven off from the tar pass with the gases into the collector main, while the pitch or residue from the 45 distillation of the tar can be collected and separately recovered as a product of the distillation. If the distillation of the tar is carried to the point where heavy pitch is 50 produced, a correspondingly increased

amount of heavy oils are driven off from the tar during the distillation and pass over with the gases into the collector main. These heavy oils tend to separate out with the tar in the collector main, and if the resulting 55 tar is returned for further distillation to produce pitch therefrom, the heavy oils are again distilled and returned to the collector main and tend to increase in amount as they are repeatedly distilled by the hot coke oven 60 gases and condensed in the collector main.

The improved method of operation of the present invention enables this objection to be overcome, and enables the oils or distillates 65 driven off during the distillation of tar to be recovered in the ordinary by-product recovery system of the coke oven plant without the accumulation of heavy products of the distillation in the tar to be redistilled.

The present invention relates particularly 70 to operations in which tar containing high boiling oils is distilled to drive off the heavy oils therefrom and leave a pitch residue; and the invention enables these heavy oils 75 to be recovered in the by-product recovery system of the battery without accumulating in the heavy tar to be distilled.

According to the present invention, I provide 80 separate collecting means, such as a separate collector main, for the modified uptake pipes which are employed for the distillation of tar, so that the distillates from such distillation do not enter the ordinary collector main, but are kept separate in the 85 separate collector main; and I pass the gases and vapors from such separate main to the condensing system connected with the ordinary cross-over main of the battery. In this way, I keep separate the heavy oils distilled 90 from the tar, and recover them separately either in the separate collector main, or pass them over to the condensers of the battery and condense and recover them in admixture with the lighter tar and oils from the 95 normal operation of the battery.

From the standpoint of apparatus or equipment, I provide, in addition to the ordinary collector main and condensing system of the battery, a separate short collector main or mains and I connect the uptake 100

pipes which are modified to permit tar distillation therein, with the separate short collector main so that the gases and vapors resulting from the distillation are collected therein; and I then pass the gases and vapors from the separate main to the direct or indirect coolers forming part of the main condensing system of the battery. The modified uptake pipes are also advantageously connected with the usual collector main, and provided with valves for enabling the gases from the uptake pipes to be discharged either into the ordinary main, when not employed for distillation, or into the separate collector main, when employed for such distillation.

The distillation of the tar, in the modified uptake pipes, is effected by the heat contained in the hot coke oven gases passing upwardly therethrough, for example, by atomizing or spraying the tar or otherwise bringing it into intimate contact with the hot coke oven gases immediately after they leave the coke ovens, or at least while they are at a temperature high enough to accomplish the desired distillation. This distillation of the tar by the hot coke oven gases gives pitch or a heavy residue, and increases the vapor content of the gases by the vapors driven off from the tar during the distillation. Some of the heavier constituents of the gas are removed therefrom by the scrubbing action of the tar spray and are added to the pitch residue, while the remainder of the condensable constituents of the hot coke oven gases pass with the added vapors from the distillation to the separate collector main.

The number of ovens provided with the modified uptake pipes and employed for the distillation of tar, can be varied. A few only of these modified uptake pipes are sufficient for distilling the tar from an entire battery. However, by providing connections between the modified uptake pipes and the ordinary collector main, as well as with the separate collector main, it is possible to provide a considerable number of the modified uptake pipes and to use as many or as few of them as desired for tar distillation. Those which are not so employed can be opened to the ordinary collector main, while those which are employed for tar distillation can be opened to the separate collector main.

The separate collector main, which collects the gases and vapors from the distillation, may be provided with tar or ammonia liquor spray to assist in condensing the heavier constituents, and the tar or oil thus condensed can be drawn off from the separate collector main as one of the products of the process. The gases and vapors that remain after such preliminary condensation are then passed over to the ordinary coolers

or condensers to which the gases and vapors from the ordinary collector main pass for the recovery of light tars and oils therefrom. In this way, a separate condensing system is not necessary, while the heavier oils from the distillation of the tar are prevented from entering the ordinary collector main and becoming admixed with the heavy tar separated therein.

From the standpoint of battery operation, the greater part of the battery may be operated in the ordinary way with discharge of the gases from the ovens into the common collector main which may be provided with tar and ammonia liquor sprays, and in which the heavier tar will be thrown down and separated as a heavy tar product. The remaining gases and vapors then pass over through the cross-over main to the coolers or condensers which may be of the direct or indirect type and in which the gases are further cooled to separate the greater part of the remaining condensable constituents therefrom.

That part of the battery which is provided with the modified uptake pipe leading to a separate collector main, is operated with tar sprays to effect distillation of the tar by the hot coke oven gases in the modified uptake pipes and the resulting admixed gases and vapors then pass to the separate collector main where some of the heavier constituents may be condensed and separated, and the remaining gaseous and vapor mixture then passes to the condensers or coolers above mentioned.

The tar which is distilled according to the present process, may be tar produced at the same coal carbonizing plant at which it is distilled, or it may be tar from another coal carbonizing or other plant. It may be a heavy tar, a light tar, or tar of widely varying properties. It may be a heavy tar containing only part of the oils from the coal distillation, or it may contain all or practically all of the condensable oils, as where all of the tar constituents are normally collected or condensed together.

The manner in which the tar is brought into direct contact with the hot vapors can be varied. A suitable atomizing or spray nozzle, to which the preheated and thinly fluid tar is supplied under a sufficient pressure to bring about atomizing or spraying and resulting intimate contact of the tar with the hot gases, can be located in the upper part of the modified uptake pipe to bring the tar into intimate contact with the hot gases.

A single tar spray can be used in each of the individual uptake pipes, or a plurality or series of such sprays, and the rate at which the tar is sprayed, as well as its temperature, can be regulated and controlled to obtain a greater or less degree of distillation

of the tar and the production of distillates of desired characteristics, and of harder or softer pitches or pitch-like products.

The gases escaping from the top of a coke oven are at a high temperature, e. g., around 600° to 700° C., or in some cases much higher. The temperature of these gases is sufficiently high so that effective distillation of the tar can be accomplished by an intimate and regulated spray of the tar into the hot gases. By employing the gases at practically top-of-oven temperature their maximum heating and distilling effect is utilized. The amount of tar and the intimacy and time of contact of the particles of the tar spray with the gases, and the nature and amount of oil distilled therefrom, can be varied.

By regulation of the rate and type of tar spray and its temperature of preheating, and by redistillation when necessary, it is possible to regulate the hardness of the pitches produced, and produce softer or harder pitches, as desired, and oils of different characteristics may be formed. The further distillation of the pitch first produced to recover additional oil therefrom, can be carried out in the same uptake pipe still, or it may be subjected to further distillation in another uptake pipe still. The invention is particularly advantageous in that the distillation of the tar or pitch effects the vaporization of some of the heavier oils which would normally be thrown down in the ordinary collector main as a part of the heavy tar and which, if so thrown down, would be returned and redistilled repeatedly with resulting accumulation of the amount of these heavy oils in the heavy tar. By separately collecting these heavy oil vapors in the separate collector main, they can then be passed over to the ordinary condensing system and kept out of the heavy tar. The invention thus provides a means for distilling the heavy tar and separating heavy oils therefrom and recovering these heavy oils in the ordinary condensing system of the coke oven plant.

The invention will be further illustrated by the following more detailed description taken together with the accompanying drawings, which show apparatus embodying the invention and adapted for the practice of the process of the invention, but it is intended and will be understood that the invention is illustrated thereby but not limited thereto.

In the accompanying drawings,

Fig. 1 shows a plan view of part of a coke oven battery modified to embody the present invention and to permit operation of the process of the invention,

Fig. 2 is a view in elevation showing part of one end of the battery,

Fig. 3 is an enlarged sectional view

through the modified uptake pipes and collector main, and,

Fig. 4 shows one form of modified uptake pipes.

The invention is of more or less general application to different types and construction of by-product coke ovens such as Semet-Solvay ovens, Koppers ovens, etc., but will be more particularly described and illustrated in connection with by-product coke ovens of the Semet-Solvay type.

In the drawings, the coke oven is illustrated conventionally at 1 and has the usual gas outlet 2 for the escape of the hot coke oven gases. The outlet pipe 3 is seated in a suitable seal over the gas outlet 2 and connects at its upper end with the lower end of the casing 4. The upper end of the casing 4 connects with the uptake L 5 which leads to the ordinary collector main 6 and to the separate collector main 7, valves 8 and 9 being provided for connecting the uptake L with one or the other of these mains as desired.

The casing 4 is enlarged to provide a space around the inner pipe member 10 which extends upwardly into the enlarged casing 4. The lower ends of the pipe 10 and the casing 4 are preferably integral or otherwise arranged to provide an annular receptacle for the collection of the pitch or residue from the distillation.

Located within the casing 4 and above the end of the pipe 10 is a baffle or hood 11 and above this is a spray head 12 connected with a pipe 13 for spraying tar to be distilled. An outlet 14 for pitch or residue is located at the bottom of the enlarged casing 4 for discharging the pitch or residue from the annular space at the bottom of the casing, to a tank or other receptacle 14'. The casing 4 is attached at its lower end to the outlet pipe 3 which in turn is sealed in the roof structure of the ovens. At its upper end the casing 4 is connected with the uptake L 5.

The casing 4 has a series of doors or openings 15 near the bottom to permit inspection and cleaning. The casing also has an upper door 17 carrying the baffle or hood 11, the arrangement being such that when the door is open the baffle 11 is removed from the casing. The casing 4 also has overflow outlet 18 located some distance from the bottom of the annular space at the bottom of the casing.

The connection from the uptake pipe stills to the collector mains may be provided with a spray 19 for cooling or assisting in cooling condensable constituents of the gas and for spraying the valves 8 and 9. Additional spray nozzles 20 may also be provided in the ordinary collector main 6 and other sprays 21 in a separate collector main 7. Ammonia liquor can be used in such

sprays, or tar, or a mixture of liquor and tar.

The coke oven battery illustrated in Fig. 1 has the ordinary pipes 22 connected with the usual collector main 6. The usual cross-over main is indicated at 23, leading to the coolers or condensers 24 and 25 connected to decanter 26. The exhauster for drawing the gases through the system is indicated at 27. 10 This part of the system comprising the uptake pipes 22, collector main 6, cross-over main 23, coolers, etc., is the ordinary by-product coke oven system.

The tar collected in the collector main and cross-over main is shown as running to a tar collecting tank 28 in which the tar separates from the ammonia liquor and this tar in turn is shown as leading to a dehydrator 29 for completely freeing the tar 15 from water or preheating it for distillation. The dehydrator may be of any suitable construction. The dehydrated and pre-heated tar is then pumped by the pump 30 through the tar supply line 13 to the spray nozzles 12. Undehydrated tar may be used if desired. It is, however, advantageous to the spraying operation that the tar be pre-heated to the extent that it is in a thinly 20 fluid condition as it is delivered to the sprays.

The separate collector main has a discharge pipe 33 leading to a decanter 34 for collecting the heavy condensates separated in this separate collector main. The unden- 25 sored vapors and admixed gases pass from this separate collector main through a separate cross-over main 32 to the condensers or coolers 24 or 25 above described. The piping arrangement is such that the gases and 30 vapors from the separate collector main may pass either to the condenser or cooler 24 or to the condenser or cooler 25 or through the two condensers or coolers in series, so that the products separated out from the gases and 35 vapors may be admixed with one or the other of the products from these separate condensers or coolers, where these products are kept separate. A pipe 35 controlled by a valve 36 permits delivery of gases and 40 vapors from the pipe 32 directly to the cross-over main 23 when such operation is 45 desired.

The products thus separated and recovered in the condensers and coolers 24 and 50 25 will be composite products, being made up in part from products condensed from the main coke oven gases of the battery and in part from the distillates from the separate distilling system. The relative proportions of these separate condensed constituents 55 can be regulated by regulating the extent to which the admixed gases and vapors are cooled and scrubbed in the separate collector main, and by regulating the condenser or cooler into which the separate

gases and vapors pass for further condensation. A further regulation is possible by increasing or decreasing the amount of tar distilled, or the extent to which the tar is distilled. When the amount of tar to be distilled is increased, a larger number of the uptake pipe stills can be employed for the distillation and connected with the separate collector main. When the amount of tar to be distilled is decreased, a smaller number of the uptake stills will be required. In the apparatus illustrated, a greater or smaller number of the uptake pipes can be employed for the distillation and connected to the separate collector main, while those which are not so employed can be connected with the ordinary collector main, thus keeping separate the gases employed for the distillation from those which are not so employed. 70 75 80 85

Considering the operation of a single coke oven battery, the invention makes possible the distilling of all of the heavy tar collected in the collector and cross-over mains and the driving off and recovery therefrom of volatile oils and the production of pitch, the volatile oils being carried over and collected in the ordinary condensing system of the battery. In this way, all of the heavy tar is converted into pitch and distillate 90 95 oils, and all of the distillate oils are separately recovered along with the lighter tars and oils from the normal operation of the battery.

While I have described and illustrated a particular type and construction of uptake pipe still, and a particular arrangement and size of separate collector mains, and a particular arrangement of connections with the ordinary condensing system, it will be evident that the invention in its broader aspects can be carried out in the apparatus of other constructions and that variations and modifications can be made therein without departing from the spirit and scope of the invention. 100 105 110

I claim:

1. The improvement in the operation of the by-product recovery system of a coal distillation plant which comprises collecting coal distillation gases from part of a battery and removing heavier tar constituents therefrom, distilling tar by bringing it into contact with hot coal distillation gases evolved from another part of the battery to distill volatile oils from the tar and produce pitch therefrom, collecting the resulting gases and vapors separately from the gases from the remainder of the battery, blending them with the first mentioned gases after said removal of heavier tar constituents from said first mentioned gases and cooling the blended gases so as to recover condensable constituents comprising condensates from the gases employed for the distillation of tar in ad- 115 120 125 130

mixture with condensates from the lighter constituents of the gases first mentioned.

2. The improvement in the operation of the by-product recovery system of a coke oven plant which comprises collecting coke oven gases from part of a coke oven battery and recovering heavier tar constituents therefrom, distilling coal tar to pitch by bringing it into contact with hot coke oven gases evolved from another part of the battery to distill volatile oils from the tar and produce a gas mixture containing vapors of heavier condensable constituents and lighter condensable constituents distilled from the tar, recovering the heavier condensable constituents from said gas mixture apart from the aforementioned recovery of heavier tar constituents from coke oven gases, and recovering lighter constituents from said gas mixture together with lighter constituents from the first mentioned coke oven gases by combining the gases with the gas mixture, and cooling the combined gases.

3. The improvement in the operation of the by-product recovery system of a coke oven plant, which comprises cooling coke oven gases from part of a coke oven battery to separate heavier tar constituents therefrom, recovering the heavier tar constituents and distilling them by bringing them into contact with hot coke oven gases evolved from another part of the battery thereby distilling the tar to pitch and forming a gas mixture containing volatile oils distilled from the tar, separately collecting the resulting gas mixture and combining it with said coke oven gases from which heavier tar constituents have been separated, and cooling the combined gases to separate condensable oils therefrom.

4. The improvement in the operation of the by-product recovery system of a coal distillation plant, which comprises collecting coal distillation gases from part of a battery and removing heavier tar constituents therefrom, distilling tar by bringing it into contact with hot coal distillation gases evolved from another part of the battery to distill volatile oils from the tar, cooling these gases to remove heavier condensable constituents, blending these gases with the first-named gases after said removal of heavier tar constituents and cooling the blended gases to recover lighter condensable constituents.

In testimony whereof I affix my signature.
FRED OSBORNE.
